UNITED STATES PATENT OFFICE.

SEWARD M. SAVAGE, OF CHICAGO, ILLINOIS, ASSIGNOR TO BRADLEY TRANSPORTATION COMPANY, OF ROGERS CITY, MICHIGAN, A CORPORATION OF WEST VIRGINIA.

UNDERWATER CONSTRUCTION.

Application filed February 16, 1925. Serial No. 9,605.

This invention relates to a new and improved method and apparatus for underwater construction and more particularly, to a method and apparatus adapted for building and leveling breakwaters and the like under water.

Numerous types of breakwaters and other structures which rest upon the bottom under water comprise as an element a lower portion or foundation consisting of broken stone in various sizes. In many such constructions it is essential that the broken stone be uniformly placed and the upper surface leveled to receive superposed structures.

10 This construction has heretofore generally been carried out by taking the material from barges or lighters by means of power shovels and depositing it where desired. This results in a series of piles and requires considerable work by divers in leveling the work.

I am aware that it has also been proposed to make such structures by unloading the stone from a boat by means of a continuously operating conveyor extending out on a boom from the side of the boat and moving the boat along the line of the structure. In spite of continuous sounding this method forms a somewhat irregular longitudinally 25 extending pile and even by closely placing such piles a considerable amount of underwater leveling is required.

It is an object of the present invention to provide an apparatus and method whereby 30 loose material may be continuously deposited under water and leveled or otherwise desirably shaped mechanically simultaneously with the deposit.

It is a further object to provide apparatus 35 which is relatively simple in design, construction and operation and adapted for efficiently and rapidly carrying out my method.

Other and further objects will appear as 40 the description proceeds.

45 I have illustrated certain preferred embodiments of my invention in the accompanying drawings, in which—

Figure 1 is a perspective view showing the apparatus carried by a single barge;

50 Figure 2 is somewhat similar to Figure 1 showing the apparatus carried between two barges;

Figure 3 is a perspective view showing the apparatus supported on the bottom;

Figure 4 is an enlarged side view of one 55 form of apparatus;

Figure 5 is a view of Figure 4 as seen from the right;

Figure 6 is a view similar to Figure 3 showing a further modification, and 60

Figures 7 to 10 are views showing forms of finishing templates or strike boards.

Referring first to Figure 1, the material carrying vessel has been indicated diagrammatically at 11 and is provided with the conveyor 12 adapted to continuously discharge the material. The vessel is moored beside the pile clusters 13, which are located in a line parallel to that of the breakwater to be constructed. The barge 14 is moored by 70 lines 15 to anchors set up well ahead on the line of the breakwater. These lines 15 are handled by winches 16. A stern-holding line 17 connects to a stern anchor and is handled by winch 18. A rope 19 is secured to 75 the vessel and to a cleat 20 carried by the barge. The barge carries, secured thereto, the material receiving hopper 21 having the material depositing chute 22 extending downwardly through the barge. The construction 80 of this material handling hopper and chute will be described more in detail in connection with Figures 4 and 5.

Referring now to the form of construction shown in Figure 2, the vessel 31 is provided with the continuous discharge boom 32. The pair of barges 33 and 34 are connected by cross beams 35, or otherwise, so as to maintain them in spaced parallel position. These barges may be secured to the vessel by cables 36 and 37. The barges are provided with the longitudinally extending rails 38 upon which rest the wheels 39 which are a part of the distributing hopper assembly 40. The forward line 41 is secured to an anchor set up ahead 90 on the line of the breakwater and carries the pulley 42. The drag line 43 is connected to the forward end of the distributing apparatus 40 and passes through the pulley 42 back to a winch on the distributing mechanism. The rear holding line 44 leads to an anchor set astern and the pulley 45 carried by the line 44 has the cable 46 extending through it. One end of this cable is connected to the rear of the distributor and the other 95 end goes to a winch carried by the distributor.

In the form of construction shown in Figure 3, the vessel 51 is provided with the con-

tinuous discharge boom 52 and is moored against the pile clusters 53 along the line of the breakwater. The distributing apparatus 54 rests on the top of the pile of deposited material 55. This apparatus 54 is provided with the caterpillar type of threads 56, which are driven by the internal combustion engine 57 carried by the apparatus. The apparatus is preferably divided on the plane 81, slightly above the normal water line so that during breaks in the period of operation the upper portion may be removed and not left subject to wave action. It will be understood that the drive belt will be disconnected at this time and that the apparatus may carry ballast if desirable to give it added stability.

One preferred form of hopper and distributor construction is shown in detail in Figures 4 and 5. The frame 61 is provided with the wheels 62 resting on the tracks 63 carried by the barges 64 and 65. It will be understood, of course, that instead of two barges, this construction may be supported on a single barge and extend through a central well 25 in the barge. The hopper 66 is supported by the framing 67 from the frame 61. This hopper discharges into the chute 68 and it will be noted that the upper portion 69 of the chute is narrower than the lower portion, so that there will be no tendency for material to 30 clog in the chute. As shown in Figure 5, the chute 68 is formed of a plurality of vertically extending parallel bars 70. This serves to minimize the effect of current or wave action 35 upon the chute.

The lower end of the fixed portion of the chute is supported in the frame 71, which is carried by the frame work 67. The adjustable lower end frame 72 of the chute is carried by the vertically extending support members 73 which terminate in the connector block 74. This block is supported by the screw 75 from the frame work 67. The frame 72 may be adjusted vertically by the screws 40 75, one of which is on each side of the hopper.

The frame 72 carries the plate 76 extending from its rear lower edge and this plate determines the elevation and contour of the top of the deposited material. The indicating plate 77 swings to the rear of the frame 72 and is connected to the indicator rod 78, which extends up beside the hopper and carries a pointer 79 cooperating with a scale 80 to indicate the height of the material. The 45 form of hopper shown in Figure 2 is similar in all respects to that just described. The hopper shown in Figure 1 and that shown in Figure 3 are similar in detail, but differ in that the discharge chute of the hopper is located at the forward face of the hopper rather than at an intermediate portion.

Instead of the level straight edge plate 76, members of the form shown in Figures 7 to 10 may be used or those of any desired form. 50 The member 82 of Figure 7 provides a convex

top while the member 83 of Figure 8 will form a concave surface. The member 84 of Figure 9 forms a shouldered level surface. The member 85 of Figure 10 is provided with downwardly extending spikes 86 which tend to work and consolidate the upper portion of the material as well as leveling it.

The form of construction shown in Figure 6 differs from that of Figure 3 in that it is provided with broad wheels 87 instead of the belt treads and is adapted to be moved by external power through cables 88 and 89, rather than by its own power. This structure is separable along the plane 90, above the water level.

In the use of the form of apparatus shown in Figure 1, the barge is moored so as to extend across the line of breakwater to be constructed with the lower end of the chute extending the width of the top of the pile or foundation desired. The frame 72 at the lower end of the chute, shown in detail in Figures 4 and 5, is adjusted vertically so that the edge of the plate 76 is at the proper level.

Material is now dumped into the hopper from the conveyor and passes down through the chute. When the material ceases to flow down the chute and remains in the hopper, the barge is drawn forwardly, the plate 76 defining the top edge of the pile and the plate 95 77, by its connection with the pointer 79, indicates the level in the rear of the plate as the barge and hopper move forward. The forward movement of the barge may be substantially continuous, the flow of material 100 being so related to the movement that the hopper is maintained partly full.

It will be seen that the movement of the barge is independent of that of the steamer or source of material supply, it merely being necessary that they be relatively positioned so that the discharge point be above some part of the hopper. The size of the hopper may be made such as to permit considerable relative displacement of the two units without interruption of the operation.

In the form of construction shown in Figure 2, the operation is similar to that described. Here the hopper structure may be moved independently of the movement of the supporting barge, the hopper being moved on the tracks carried by the barges. The barges may be moved with the vessel, or all three units may be moved independently if desired.

In the form of construction shown in Figure 3, sufficient of the breakwater will be constructed to serve as an original support for the apparatus, this construction being carried out in any usual manner. The apparatus will then be put in place on this part of the structure and the operation will be carried out in the same manner as has been described above. Here the apparatus rests firmly on a fixed support and is moved for 125 130

ward under its own power as the work progresses. The vessel or other source of material is moved forward, this movement being either continuous or in such increments as 5 to keep the end of the discharge boom over some part of the hopper. The construction of Figure 6 is operated in a similar manner, the motive power being externally supplied.

The apparatus has been described as having a discharge chute of the width of the 10 top of the desired placed material, but it will be obvious that in wide structures the work may be carried out by placing a series of parallel strips of material.

15 While I have shown certain preferred embodiments of my invention, these are to be understood to be illustrative only, and I contemplate such changes and modifications to meet various conditions, as may come within 20 the spirit and scope of the appended claims.

I claim:

1. Apparatus for forming underwater structures of loose materials comprising a material receiving hopper, a chute for discharging 25 material from the hopper, means for shaping the material discharged, means extending above the water level for indicating the level of the shaped material, and means for moving the hopper and chute along the line of the 30 structure.

2. Apparatus for forming structures of loose materials comprising a movable source 35 of material supply, a hopper adapted to receive material from the source of supply, and means for discharging material from the hopper to form the structure, the source of material supply and the hopper being independently movable along the line of the work.

3. Apparatus for forming structures of 40 loose materials comprising a movable source of material supply, a hopper adapted to receive material from the source of supply, and means for discharging material from the hopper to form the structure, the source of material supply and the hopper being independently supported and movable along the line 45 of the work.

4. Apparatus for forming structures of loose material comprising a hopper, means 50 for supporting the hopper from the portion of the structure already formed, and means guiding material from the hopper to extend the structure.

5. Apparatus for forming structures of 55 loose material comprising a hopper, means for supporting the hopper from the portion of the structure already formed, means guiding material from the hopper to extend the structure, and means to move the hopper and mate-

rial guide along the structure as the structure is extended. 60

6. Apparatus for forming structures of loose material under water comprising a floating source of supply, a distributing hopper, means for supporting the hopper upon the 65 completed portion of the underwater structure, and means for moving the hopper independently of the movement of the source of supply.

7. Apparatus for forming structures of 70 loose material under water comprising a floating source of supply, a distributing hopper, means for supporting the hopper above the water surface, a discharge chute extending from the hopper to the level of the underwater structure, and means carried by the 75 chute for shaping the material as it is deposited by the chute.

8. Apparatus for forming structures of 80 loose material under water comprising a floating source of supply, a distributing hopper, means for supporting the hopper above the water surface, a discharge chute extending from the hopper to the level of the underwater structure, means carried by the chute for 85 shaping the material as it is deposited by the chute, and means engaging the deposited material connected to an indicator above water to show the height of the deposited 90 material.

9. Apparatus for forming structures of 95 loose material under water comprising a floating source of supply, a distributing hopper, means for supporting the hopper above the water surface, and a discharge chute extending from the hopper to the level of the underwater structure, the chute being formed of spaced members to permit water flow therethrough.

10. The method of forming structures of 100 loose materials which comprises feeding material from a movable source of supply to a movable hopper along the line of the work and independently moving the source of supply and hopper as the work progresses. 105

11. Apparatus for forming structures of 110 loose material under water comprising a floating source of supply, a distributing hopper, means for supporting the hopper upon the completed portion of the underwater structure, and means for moving the hopper independently of the movement of the source of supply, the hopper being moved along upon the completed portion of the structure.

Signed at Chicago, Illinois, this 14th day 115 of February, 1925.

SEWARD M. SAVAGE.
